RECEPTACLE FILLER

Adolph J. Lippold, Milwaukee, Wis., assignor to
Cherry-Burrell Corporation, Chicago, Ill., a corporation

Application October 21, 1947, Serial No. 781,191

2 Claims. (Cl. 226—124)

1

This invention relates to improvements in a device for filling receptacles with liquid, such, for example, as a device for filling milk into milk bottles or containers.

It is the object of this invention, among other things, to provide an improved type of container filling machine and valve therefore, as well as an improved support for such a valve.

In receptacle fillers of the type commonly referred to as vacuum type receptacle fillers, the valve mechanism, through which liquid is discharged from a reservoir or tank for liquid into a container, is frequently positioned beneath the liquid reservoir and the liquid flows into the receptacle after the air normally present in the receptacle has been partially exhausted or is being partially exhausted therefrom. Such valve mechanisms are sometimes provided with a vent tube. Normally, such a vent tube extends from a point above the level of the liquid in the liquid supply reservoir, from which reservoir the air is constantly being exhausted, down through a supply of liquid and through the valve mechanism or filler head to a point beneath the valve mechanism. The lower end of the vent tube extending beneath the valve mechanism may communicate with the interior of a receptacle to be filled when placed in filling position or to communicate with the atmosphere when no receptacle is in filling position beneath the filling head.

During the normal operation of the improved receptacle filler, the vent tube of the improved valve serves as a means for partially exhausting air or other gases from the receptacles or containers to be filled, and when necessary also serves to withdraw excess liquid from the filled container at the completion of the filling operation after the seal between the container and the filling head has been broken.

In some of the more conventional types of valves used on vacuum type receptacle fillers, the vent tube is open constantly, thereby permitting the entry of an excess quantity of air into the partially exhausted reservoir during such periods when there are no containers in filling position at the filling heads. The entry of such excess quantities of air in many instances overloads the means for producing and maintaining the sub-atmospheric pressure condition in the space above the liquid in the liquid supply reservoir. It has also been found that at the time that the seal between the filling head and the filled receptacle is broken, there is a tendency for some of the liquid normally drawn into the vent tube from the filled receptacle to drop again from the vent tube into the filled receptacle, thereby over-

filling the receptacle or to drip onto portions of the filling mechanism when the filled receptacle is removed. Obviously, such a condition greatly detracts from the degree of exactness to which the receptacles may be filled to predetermined levels, and also contributes greatly to unsanitary conditions of the machine.

The primary object of this invention is, therefore, to provide an improved container filler of the vacuum filler type, adapted to use an improved filling head for filling containers; in which the filling head is provided with a vent tube and seal therefore, and wherein the seal is operable responsive to the opening and closing movements of the liquid valve of the filling head; in which the filling head is supported on the liquid reservoir of the filler by an improved valve support; and in which the vent tube and seal therefore are so constructed and arranged and operate in such a fashion as to enable the desired degree of control of the movement or flow of air or liquid through the vent tube.

The foregoing and other objects of this invention will be more apparent and will be more readily understood when read in connection with the drawings illustrating the preferred embodiments of the present invention, which, without desire of limitation, will be described and illustrated as an improved type of milk bottle filler and parts therefore, in which:

Figure 1 is an elevational view, partially in broken-away section, of the reservoir for liquid of the improved filler equipped with the improved type of filling heads.

Figure 2 is an elevational view, partially in section, of one of the preferred embodiments of the improved valve, mounted in operative position in the lower wall of the liquid reservoir of the filler.

Figure 3 is a perspective view of an improved support for the improved filling heads or valves.

Figures 4 and 5 are elevational views of modified vent tube seal actuators for the improved type of filling head shown in Figure 2 of the drawings.

Figures 6 and 7 are elevational views, partially in section, of modified forms of the improved filling head mounted in operative position in the lower wall of the liquid reservoir of the filler.

Figure 8 is an elevational view of the modified vent tube seal actuator for the modified valves of the type shown in Figures 6 and 7 of the drawings.

Figure 9 is a plan view of the vent tube seal actuator shown in Figure 8 of the drawings.

Figure 10 is an elevational view of the modified

2

vent tube seal actuator for the modification of the filling heads shown in Figures 6 and 7 of the drawings.

Figure 11 is a plan view of the vent tube seal actuator shown in Figure 10 of the drawings.

Referring to the drawings, in which like numerals are used to identify like elements, 1 represents a rotatable support for a rotatable supply reservoir 2 for milk or other liquids to be filled into containers. Reservoir 2 is provided with a lid or cover 3, resting on the gasket 4 placed about the mouth of the reservoir or tank 2, whereby to seal the cover 3 to the tank 2. The cover 3 is provided centrally thereof and in alignment with the rotatable support 1 with a combined rotary fluid coupling 5, provided with an axial inlet or supply conduit 6 for the milk or other liquids to be supplied to the reservoir 2, and a peripheral discharge or evacuation conduit 7 for connection to a source of vacuum. The milk or other liquid supplied from a suitable source of supply (not shown) through conduit 6 enters the tank 2 through the float valve 8, whereby a predetermined level of the body of liquid in the reservoir 2 may be maintained. By means of connections to a suitable source for the development and maintenance of a desired degree of vacuum (not shown) a predetermined pressure condition, such as sub-atmospheric, may be produced and maintained in the reservoir 2 above the level of the liquid therein.

As clearly shown in Figure 1 of the drawings, the tank 2 is preferably provided with a plurality of filling nozzles or heads 9, communicating through ports in the lower wall of the reservoir with the interior portion thereof containing the liquid to be filled into the containers. Upon an inspection of the broken-away portion of Figure 1 of the drawings, it is also apparent that each filling head or valve 9 is provided with a vent tube or pipe 10, the upper end of which extends above the level of the liquid in the reservoir 2, thereby permitting the venting or partial evacuating of air or other substance from the containers being filled through the filling heads 9 into the vacuumized space above the liquid in the reservoir 2.

In the figures of the drawings, there are illustrated several embodiments of filler heads embodying unique improvements, as well as several mechanical variations thereof, for the construction of certain portions of the improved type of filler heads.

In Figure 2 of the drawings, there is illustrated an improved bellows type of filling head, having a tubular vent stem 10 extending through an aperture in the lower wall of the reservoir 2, which aperture is defined by the downwardly turned flange 11 formed in the lower wall of the tank 2. The vent tube 10 is preferably arranged vertically and centrally in the associated aperture and extends from a point below the lower wall of the tank 2 through the associated aperture through the body of liquid in the tank and into the space above the body of liquid. That space is preferably maintained under a condition of subatmospheric pressure.

To secure the vent tube 10 in position, there is provided a vent tube support spider or bracket 12, having a sleeve 13, telescoped over and in bearing contact with the collar 14. The collar 14 is welded to or otherwise securely fixed to the outer surface of the vent tube 10 or formed integrally with the vent tube 10. Flange 15 at the lower end of the collar 14 abuttingly engages

the adjacent edges of the sleeve 13. Removable clip pin 16 engaged in groove 17 in the outer periphery of the collar 14 overlaps and abuts against the upper end of the sleeve 13, thereby locking the vent tube 10 in position with respect to the sleeve 13 of the support spider 12.

Sleeve 13 of the vent tube support spider or bracket 12, as illustrated in Figures 2 and 3 of the drawings, is maintained in fixed position with respect to the aperture in the lower wall of the tank 2 by radially extending spacing arms 18, preferably formed integrally with the sleeve 13 on the outer surface thereof and preferably spaced at angles of 90 degrees about the outer periphery of the sleeve 13. Each of the arms 18 is of the same radial depth which is also sufficient to enable the engagement of each of the arms 18 with the adjacent portion of the edge of the downwardly turned flange 11, thereby establishing axial alignment of the spider 12 and the port defined by the circular and downwardly turned flange 11. To prevent axial motion of the spider 12, each of the arms 18 is provided adjacent its upper extremity with a radially and outwardly extending finger 19, of sufficient length to extend beyond the flange 11 and overlap and engage the adjacent portion of the inner surface of the wall of the tank 2 around the flange 11. Three of the arms 18 are provided adjacent their lower extremities with radially and outwardly extending fingers 20 of sufficient length to abuttingly overlap and engage the adjacent edge of the flange 11. Flange 11 is provided with an inner peripheral notch or slot 21 of a sufficient size to permit the movement individually of the fingers 20 therethrough.

In the assembly of the spider 12 in the aperture defined by the flange 11, the spider 12 is inserted into the aperture slightly off center with respect thereto, with one of the fingers 20 aligned with the notch 21. The spider 12 is then moved into axial alignment in the aperture defined by the flange 11, so that the remaining two of the fingers 20 are placed in overlapping, abutting engagement with and overlapped by the edge of the flange 11, and the third finger 20 is then moved downwardly through the slot 21, whereupon the spider 12 is then rotated so as to lock the spider 12 to the flange 11.

The vent tube 10 is provided at its lower extremity with an apertured valve element or member 22, which is fixed to the end of the tube 10 in such a fashion that the aperture thereof communicates with the passage of the tubular vent stem 10. Valve 22 is provided with an upper conical surface for engagement with a valve seat 23 at the lower end of the liquid discharge tube 24, superimposed over the vent stem 10. The tube 24 is arranged for axial, reciprocal motion with respect to the valve plug 22, thereby permitting the movement of the valve seat 23 away from the valve plug 22, or to urge seat 23 against the adjacent surface of the valve plug 22. A slightly compressed, resilient and flexible, tubular bellows-shaped element 25 is disposed intermediate the upper end of dispensing tube 24 and the lower surface of the adjacent portion of the wall of the tank 2. Bellows 25 is so arranged as to be in sealing contact at its lower end with the upper portion of the discharge tube 24, and in sealing contact at its upper end with the adjacent lower surface of the flange 11 and the tank 2. The bellows 25 is arranged axially with respect to the vent tube 10 and the aperture defined by the flange 11. A slight compression of the bel-

lows 25 is secured by the selection of the appropriate axial lengths of the bellows 25 and associated discharge tube 24. The length of the bellows 25 must be slightly in excess of the space between the valve 22 and the lower surface of the tank 2.

The seal of the bellows 25 against the tank 2 and the flange 11 results from the axial compression of the bellows 25. The seal of the bellows 25 to the upper end of the dispensing tube 24 results in part from the axial compression of the bellows 25 and also results in part from the rotary compression of the lower lip or bead 26 of the bellows 25 against the grooved flange 27 positioned at the upper end of the discharge tube 24, over which flange 27 the bead 26 has been stretched and as thus tensioned nests in groove 28. By virtue of the simultaneous application of compressive and tensioning force to certain portions of the bellows 25, the general dimensions of which are illustrated in Figure 2 of the drawings, a reasonable degree of distortion resulting from axial compression of the bellows 25 is possible without collapsing the bellows.

As illustrated in Figure 2 of the drawings, the liquid discharge tube 24 is provided with a container engaging and seal element 29. The element 29 is preferably of the type illustrated in Patent No. 2,171,757, and is also provided with a radially extending condensate deflector 30, overhanging the container seal element 29.

To assure the maintenance of axial alignment during the opening and closing of the liquid discharge tube 24, incidental to the axial reciprocation of the tube 24 with respect to the valve plug 22, guide studs 31 are fixed to the upper end of the tube 24 and extend through the bellows 25 through the associated aperture in the lower wall of the tank 2 and into closely spaced relation with respect to the outer surface of the sleeve 13 of the spider 12. Preferably, four of such guide studs 31 are provided and when the valve is assembled in operative position the guide studs 31 are placed intermediate the radially extending arms 18 of the vent tube support spider 12.

Due to the positioning of the studs 31 close to the sleeve 13, any slight motion of the discharge tube 24, which is not in axial alignment with the vent tube 10 upon which the valve plug 22 is supported, will cause the engagement of one or more of the guide studs 31 with the sleeve 13 to thereby prevent any undue misaligning motion of the liquid discharge tube 24 with respect to the vent tube 10 and the valve 22.

The upper end of the vent tube 10, which extends above the level of the body of liquid in the reservoir 2, is provided with a vent cap 32, made preferably of resilient material, such, for example, as rubber. The cap 32 is of such a configuration as to make it readily align itself into proper sealing and seating position on the top of the vent tube 10 and to make it readily attachable to a motion transmitter or vent tube actuator 33. The vent tube actuator 33, illustrated in Figure 2 of the drawings, is formed preferably of a relatively heavy strip of material bent into what may generally be referred to as an S-shape with apertures 34 in the lower and middle horizontal elements of the S-shaped actuator 33. As thus constructed, the lower and middle portions of the actuator 33 may be telescoped over the vent tube 10 by the extension of the upper portion of the vent tube 10 through the openings 34. The upper horizontal portion of the S-shaped vent tube actuator 33, as illus-

trated in Figure 2 of the drawings, is provided preferably with a small opening for receiving a tab, formed on the top of the vent tube seal 32, whereby the vent tube seal is removably secured to but well supported on the vent tube actuator 33. When the vent tube cap or seal actuator is assembled in the manner described on the vent tube 10, with the closure 32 in sealing position on the vent tube 10, the lower horizontal arm 35 is spaced slightly from the upper extremity of the guide studs 31. Upon the upward opening movement of the liquid discharge tube 24 of the filling head 9, the guide studs 31 will be moved upwardly into engagement with the lower horizontal arm 35 of the vent tube cap actuator 33, and upon the continued upward opening movement of the discharge tube 24, the vent tube cap actuator 33 will be raised upwardly a sufficient distance to remove the vent tube closure or seal 32 from the upper end of the vent tube. Such movement of the seal 32 establishes through the vent tubes 10 communication between the partially exhausted upper portion of the tank 2 and the space beyond the valve plug 32.

As a result of this arrangement, it immediately becomes obvious that when a container is placed in filling position below the filling head 9 and is urged against the bottle seal 29 with sufficient force to move the liquid discharge tube 24 upwardly, thereby opening the discharge tube, and thereby also opening the upper end of the vent tube by the removal of the seal 32, air entrapped in the container will be permitted to escape through the vent tube into the partially evacuated upper portion of the tank 2, and liquid will be permitted to flow from the tank 2 through the discharge tube 24 into the container. When the container has been filled, and the container is lowered away from the filling head, the compressed bellows 25 will again lower the discharge tube 24, urging the valve seat 23 into engagement with the valve plug 22, to thereby discontinue the flow of liquid from the tank 2 through the discharge tube 24. Upon a continued lowering of the filled container, the pressure of the container against the bottle gasket 29 will be sufficiently released to enable the breaking of the seal between the interior of the bottle and the filling head, as a result of the re-expansion of the depressed ribs on the filling head 9, to permit the entry of atmospheric air or other suitable gas into the mouth of the filled bottle or container through between the container and the container seal 29.

Obviously, during the operation of filling the containers, a certain quantity of liquid may enter the vent tubes 10 when the containers have been filled and may then rise to a level in the vent tube 10 comparable to the level of the body of liquid in the reservoir 2. The liquid which has thus entered the vent tube 10 is retained therein when the filled container is removed from the filling head 9 by virtue of the fact that the top of the vent tube 10 is sealed by the cap 32 at approximately the same time that the liquid discharge tube 24 is sealed by the valve 22. The sub-atmospheric pressure condition existing intermediate the column of liquid in the vent tube 10 and the vent tube closure cap 32 is such as to prevent the flow of liquid out of the lower end of the vent tube 10 when the filled container is removed therefrom.

In Figure 4 of the drawings there is illustrated a modified form of vent tube actuator in which the relatively heavy S-shaped actuator 33 is

replaced by a relatively heavy tubular element 36, telescoped over a portion of the vent tube 10. The element 36 is provided at its upper end with an apertured, curved finger 37 for the support of the vent tube cap 32, all of which is accomplished in a manner comparable to that hereinbefore described with respect to the vent tube actuator 33. The tube 36 is provided at its lower extremity with a plate 38 for engagement by the guide studs 31.

A further modification of the vent tube actuator, for use on the type of bottle filling valve or filling head illustrated in Figure 2 of the drawings, is shown in Figure 5 of the drawings. In this further modification there is provided a relatively heavy bar 39, spaced parallel to the vent tube 10, and having laterally extending preferably circular apertured arms 40. The apertures of the arms 40 are telescoped over the vent tube 10, with the lower arm 40 spaced slightly away from the upper extremity of the guide studs 31. At the upper extremity of the bar element 39 there is provided a laterally extending bracket 41, to which the vent tube cap 32 is secured, in a manner comparable to that heretofore described with respect to the attachment of the vent tube cap 32 to the vent tube actuator 33.

More conventional forms of filling heads are illustrated in Figures 6 and 7 of the drawings. As illustrated in both of these Figures 6 and 7 of the drawings, the portions of the filling head which extend downwardly from the filling reservoir 2 consist in each instance of a sectional, liquid discharge tube, comprised of the lower outer section 42 telescoped over the upper section 43. The upper end 43 of the upper one of the sectional discharge tubes for the filling heads, shown in Figures 6 and 7 of the drawings, are in each instance secured in a conventional manner to the flange 11, defining an aperture in the lower wall of the reservoir 2. An enlarged flange at the upper end of the tubular section 43 overlaps the inner face of the flange 11 in the lower wall of the tank 2. A coupling nut is threaded to an enlarged portion of the outer surface of the section 43 immediately adjacent the flange 11, thereby clamping the section 43 to the lower wall of the tank 2. Conventional type of support arms extend from the upper end of the section 43 into the interior of the tank 2 for the rigid support of the sleeve 13. A vent tube 10 is secured into the sleeve 13 in the manner as hereinbefore set forth in the description of the support arrangement for the vent tube 10 for the modified type of filling head, illustrated in Figure 2 of the drawings. To seal the liquid passage of the filling head the lower end of the vent tube 10, which extends through sections 42 and 43 of the telescoped discharge tube, is provided with a valve plug 22 to engage a valve seat 23, formed in the lower extremity of the section 42 of the liquid discharge tube. A compressed spring 44 is telescoped over the tubular sections of the dispensing tubes 42 and 43 intermediate a flange on the outer surface of the section 42, and the flange at the upper portion of the section 43, for urging the outer telescoped section 42 downwardly, thereby to engage the valve seat 23 with the valve 22.

In the modification of the filling head illustrated in Figure 6 of the drawings, there is provided a vent tube seal actuator 45, having a base portion 46, seated in a constricted throat in the inner face of section 42 of the tubular liquid discharge passage, and a vertical riser 47, which

extends upwardly from the base 46, substantially parallel to the vent tube 10. At the upper end of the vent tube 10, there is provided a spring clip 48, having a lower leg 49, consisting of two branches and provided with aligned apertures, which apertures may be telescoped over the vent tube 10 when the branches are slightly compressed, thereby providing a suitable clamping arrangement, whereby the leg 49 may be securely mounted in place on the vent tube 10. Spring clip 48 is also provided with an apertured flexible upper leg 50, in which aperture the tab of the vent tube closure cap 32 is secured. The flexible spring arm 50 is adapted to move the vent tube cap 32 into sealing position upon the end of the vent tube 10. The movement of the flexible spring arm 50, whereby the end of the vent tube 10 is sealed and unsealed, results in response to the upward and downward movement respectively of the vent cap actuator 45, which movements, in turn, result from the upward and downward movements, respectively, of the section 42 of the liquid discharge tube of the filling head shown in Figure 6 of the drawings.

The liquid discharge tube 42 is moved upwardly and downwardly in the opening and closing operations of the filling head illustrated in Figure 6 of the drawings. The motion of the vent cap actuator 45 is transmitted to the flexible spring arm 50 by the abutment of the upper end of the vertical riser portion 47 of the actuator 45 against the lower face of the spring arm 50. The riser 47 extends through a suitable guide opening in the lower arm 49 of the spring clip 48 and is thus guided in its upward and downward motion.

In Figure 7 of the drawings, the vent cap 32 at the upper end of the vent tube 10 is actuated upwardly by means of the vent cap actuator 45 coacting with a slightly modified form of weighted vent cap holder 33 of the type illustrated in Figure 2 of the drawings. In the arrangement illustrated in Figure 7 of the drawings, the vent cap actuator 33 is used primarily to cause the proper lowering of the vent cap 32, while the actuator 45 is used for the prompt raising of the vent cap 32, when the tubular section 42 of the liquid discharge passage is moved away from the valve 22.

In Figure 8 of the drawings, there is illustrated a modified arrangement of parts for the actuation of the vent cap 32. In Figure 8 of the drawings, the vent cap actuator 45 is operatively connected to a relatively heavy vent cap holder 51, which is telescoped over the upper end of the vent tube 10, and is provided with an apertured lug-like upper portion 52 for receiving the vent cap 32. An apertured, laterally extending boss 53 provides the means for connecting the vent stem actuator 45 to the vent cap holder 51.

A slightly modified vent cap holder 54 is illustrated in Figures 10 and 11 of the drawings. Similar to the vent cap holder 51, the holder 54 is of a relatively heavy construction and is telescoped over the upper end of the vent tube 10 and is provided at its upper portion with an inwardly extending apertured arm 55 for supporting the vent cap 32. The vent cap actuator 45 for use in connection with the modified vent cap holder 54, illustrated in Figures 10 and 11 of the drawings, is provided with a hook-like portion at its upper extremity for telescoping over the outer surface of the vent cap holder

54 to engage the lower surface of the flange 57. Upon the upward motion of the vent cap actuator 45, the vent cap holder 54 and the vent cap 32 are moved upwardly to unseal or open the upper end of the vent tube 10. Upon a lowering of the vent tube actuator 45, the vent cap holder 54 will automatically, due to its own weight, descend with the vent cap actuator 45, thereby replacing the vent cap 32 on the upper end of the vent tube 10. The operation of the vent cap holder 51, illustrated in Figures 8 and 9 of the drawings, is comparable.

In the foregoing description there have been set forth several modifications of an improved filling head which may be used to particular advantage in the filling of containers from a reservoir, in which a condition of sub-atmospheric pressure is maintained above the body of the liquid therein.

The applicant's invention provides an inexpensive arrangement of parts, whereby to accomplish the accurate filling of a container from a partially evacuated liquid reservoir, and whereby the liquid, which may from time to time find its way into the air vent tube during the filling operations, is prevented from draining from the vent tube into a filled container, or from draining from the vent tube onto the filling mechanism.

Having thus described and illustrated the preferred embodiments of this invention in an improved container filling apparatus and improved filling heads therefore, the invention is not to be restricted to the specifically illustrated embodiments thereof, as set forth in the drawings, and as heretofore described, except insofar as may be made necessary by the prior art disclosure and the appended claims.

The invention is hereby claimed as follows:

1. A valve mechanism for controlling the flow 40 of liquid from a ported supply tank into a receptacle comprising, in combination, a liquid supply tube having an upper and a lower end, means for establishing communication between said liquid supply tube and the interior of said supply tank, a receptacle sealing member carried by said supply tube, a valve seat in the lower end of said supply tube, a vent tube disposed substantially axially within said supply tube and having the upper end thereof extend above the 50 level of the liquid within said supply tank, an apertured valve carried by the lower end of said vent tube for valving coaction with said valve seat and having the aperture thereof communicating with said vent tube, a vent tube seal for sealing 55

the upper end of said vent tube, vent tube seal actuating means responsive to the movement of said supply tube when said valve seat is moved away from said valve removing thereby said vent tube seal from said vent tube, said vent tube seal actuating means comprising a relatively heavy vent tube seal release element slidably mounted on said vent tube and normally supported by said vent tube seal, and stud means secured to said supply tube and extending upwardly into said supply tank into close proximity and in alignment with said vent tube seal release element for the transfer of motion from said supply tube to said vent tube seal release element when said supply tube is moved upwardly.

2. In a support for supporting stem means in an aperture in a wall, a stem extending through the aperture in the wall, a peripheral flange on said stem, a bearing element encompassing said stem in bearing contact therewith and having one end thereof abutting said flange, detent means secured to said stem and abutting the other end of said bearing element, relatively short finger means on the outer periphery of said bearing element extending radially therefrom to engage one side of said wall, relatively longer finger means corresponding to said relatively short finger means and spaced therefrom to engage the opposite side of said wall, and a slot in said wall 20 at the edge of said aperture whereby at least one of the relatively short finger means may be passed through said slot when assembling said support 25 on said wall.

30 35 ADOLPH J. LIPPOLD.
